CLAIM

The ornamental design for a tank as shown and described.

DESCRIPTION

FIG. 1 is a front, right-side perspective view of a tank showing an embodiment of my design with a lid removed; FIG. 2 is a rear, left-side perspective view thereof with the lid removed;

FIG. 3 is a front, right-side perspective view thereof;

FIG. 4 is a top plan view thereof;

FIG. 5 is a bottom plan view thereof;

FIG. 6 is a right-side elevation view thereof;

FIG. 7 is a left-side elevation view thereof;

FIG. 8 is a front elevation view thereof; and,

FIG. 9 is a rear elevation view thereof.

The broken lines shown in the drawings represent portions of the tank that form no part of the claimed design.
